Atty.

UNITED STATES PATENT OFFICE

CHARLES S. HADDLESAY, OF ELMHURST, ILLINOIS

CONTROL MONORAIL CAR APPARATUS

Application filed March 6, 1931. Serial No. 520,735.

My invention relates to monorail conveyor apparatus.

One of the objects of my invention is to provide controlling apparatus for monorail cars of the suspension type which will allow only one car at a time to be released at the desired time.

A further object is to provide such apparatus in which the cars are delivered one at a time to a conveyor and in which the release of the car is controlled by the conveyor movement.

Further objects will appear from the description and claims.

In the drawing, in which one form of apparatus embodying my invention is shown,

Figure 1 is a cross-sectional view of a monorail track showing the car associated therewith;

Fig. 2 is a side elevational view of the car release controlling apparatus;

Fig. 3 is a plan view of the construction of Fig. 2; and

Fig. 4 is a perspective view of the movable track section and its support.

Referring to the drawing in detail, the construction shown therein comprises an inclined track section 1 down which the cars 2 may move by gravity, a rockably mounted car-holding and releasing member 3 which, when moved from its lower to its higher position, permits the entire string of waiting cars to advance a step, and which, when moved from its raised to its lowered position, releases the foremost waiting car and prevents movement of the following cars, an endless conveyor 4 adjacent said inclined track section, having a plurality of car pick-up devices 5 mounted in spaced relation therein, and means controlled by the movement of the pick-up devices for controlling the rocking movement of the rockable release member.

The rockable release member comprises an oscillatable U-shaped member pivotally mounted on a pair of rock pins 6 which in turn are mounted in the spaced bearing members 7. This oscillatable U-shaped member is provided with upper and lower spaced stop portions 8 and 9. When the rockable release

member 3 is moved from its lower position (shown in full lines) to its raised position (shown in dotted lines), the upper stop portion 8 is moved from its obstructing position in front of the rollers 10 of the front car, but the lower stop portion 9 is brought into obstructing position so that the string of cars can advance only a definite amount, which definite amount is designed so as to stop the string of cars in a position so that when the rockable release member is moved from its upper to its lower position, the upper stop portion 8 will enter just behind the foremost car of the string and just in front of the next-succeeding car. During this downward movement, the lower stop portion 9 moves below the path of travel of the wheels of the foremost car and this foremost car then moves by gravity down the inclined track coming to rest at the position indicated at A where it will be seized by the next pick-up member 5 which comes along.

As indicated above, the up and down movement of this release member is controlled by the movement of the pick-up devices 5 on the conveyor chain. The transmission from the pick-up device to the rockable release member comprises an operating cam or lever 11 mounted on a rock shaft 12 and engaged by the pin 13 on which the pick-up device 5 is mounted, a pair of rock arms 14 secured to this rock shaft, a pair of links or connecting rods 15 pivotally connected at 16 with these rock arms, respectively, and a pair of rock arms 17 pivotally connected at 18 to the links 15 and mounted on the rock pins 6 which are secured to the U-shaped oscillatable release member 3. A suitably-designed coil tension spring 19 is provided, tending to hold the oscillatable release member in its raised position.

When a car is in position at A, waiting for a pick-up device to come along, its weight holds the rockable release member in its lower position because of the fact that a small section 20 of the track is carried by this rockable release member and the weight of the car resting on this portion is sufficient to hold the release member in its lower position against the action of the lifting spring 19.

I will now briefly outline the operation of the releasing apparatus.

For the initial condition, we will assume that there is a car in position at A, waiting 5 to be picked up, thus holding the release member in its lower position, and that a number of cars are being held back by the upper stop portion 8. When a pick-up hook comes 10 along, it will drop down from the curved guide member 21 and fall behind the rollers of the car waiting at A and pick up this car and remove it from the track section 20 carried by the release member. This allows 15 the release member 3 to move to its upper position under the action of the lifting spring 19. This moves the upper stop portion 8 away from the front car and thereupon the entire string of waiting cars moves forward 20 a step until the rollers of the front car engage the lower step portion 9, thus bringing 25 the whole string of cars to a stop.

As the pick-up hook 5 moves along, the cross pin 13 on which it is mounted will come 30 into engagement with the bent lever or cam 11 which, through the transmission previously described, will move the rockable release member 3 to its lower position. This moves the upper stop portion 8 down behind 35 the rollers of the front car and in front of the rollers of the succeeding car and also moves the lower stop portion 9 downward from in front of the rollers of the front car, releasing this front car which rolls by gravity along the inclined track section 20 to the 40 waiting position indicated at A.

The conveyor construction may be of any suitable type comprising a pair of chains 22 running over spaced sprockets 23, the cross pins on which the pick-up hooks are mounted 45 having their ends mounted in the links of the conveyor chain.

It will be noted that if for any reason the pick-up hook should fail to grab the waiting car, no more cars will be released, as this 50 waiting car holds the release device in obstructing position because of the fact that its weight is resting on the small track section 20 carried by the rockable release member.

The feeding and releasing apparatus may 55 be controlled in various ways and may be used for delivering cars one at a time to any suitable type of conveying mechanism, either power or gravity.

While only one specific embodiment of the 60 present invention has been shown and described herein, it will be understood that various changes and modifications in the details of structure and arrangement of the parts may be made without departing from the spirit and scope of the invention. This embodiment of the invention having been shown and described, therefore what is claimed as new is:

1. Apparatus for handling monorail sus- 65 pension cars comprising an inclined track

section along which the cars travel by gravity, a traveling conveyer adjacent said track section having car pick-up devices mounted in spaced relation thereon, and means controlled by the movement of the conveyor for delivering the cars one at a time from the inclined track section to the pick-up devices, said delivering means comprising a member movable to one position to permit the waiting cars to advance a step and movable to another position to release the foremost waiting car and prevent movement of the following cars.

2. Apparatus for handling monorail suspension cars comprising an inclined track 80 section along which the cars travel by gravity, a traveling conveyor adjacent said track section having car pick-up devices mounted in spaced relation thereon, and means controlled by the movement of the conveyor for 85 delivering the cars one at a time from the inclined track section to the pick-up devices, said delivering means comprising a member movable to one position to permit the waiting cars to advance a step and movable to another position to release the foremost waiting car and prevent movement of the following cars, and means whereby the weight of the released car holds the movable member in said movement-preventing position until 90 the released car is carried away by the pick-up device.

3. Apparatus for handling suspension cars comprising a downwardly inclined track section along which the cars travel by gravity, 100 an upwardly inclined track section to which the cars are delivered from the downwardly inclined section, a traveling conveyor running parallel to said upwardly inclined track section and having car pick-up devices 105 mounted in spaced relation thereon, releasable retaining means controlled by the movement of the conveyor for delivering the cars one at a time from the downwardly inclined track section to the pick-up devices, said 110 retaining means comprising a pair of stops, one for cooperating with the foremost detained car and one for cooperating with the car next to the foremost detained car, and means for controlling said stops so that when moved from one position to another all the detained cars are permitted to advance a step and when returned the foremost detained car is separated from the others and released to be moved into position to 115 operate with the pick-up devices.

4. Apparatus for handling suspension cars comprising a downwardly inclined track section along which the cars travel by gravity, 120 an upwardly inclined track section to which the cars are delivered from the downwardly inclined section, a traveling conveyor running parallel to said upwardly inclined track section and having car pick-up devices 125 mounted in spaced relation thereon, releas-

able retaining means controlled by the movement of the conveyor for delivering the cars one at a time from the downwardly inclined track section to the pick-up devices, said retaining means comprising a pair of stops, one for cooperating with the foremost detained car and one for cooperating with the car next to the foremost detained car, means for controlling said stops so that when moved from one position to another, all the detained cars are permitted to advance a step and when returned and foremost detained car is separated from the others and released to be moved into position to cooperate with the pick-up devices, and a pivoted track section movable with said stops to which said separated car is released.

5. Apparatus for handling suspension cars comprising a downwardly inclined track section along which the cars travel by gravity, an upwardly inclined track section to which the cars are delivered from the downwardly inclined section, a traveling conveyor running parallel to said upwardly inclined track section and having car pick-up devices mount-

ed in spaced relation thereon, releasable retaining means controlled by the movement of the conveyor for delivering the cars one at a time from the downwardly inclined track section to the pick-up devices, said retaining means comprising a pair of stops, one for cooperating with the foremost detained car and one for cooperating with the car next to the foremost detained car, means for controlling said stops so that when moved from one position to another all the detained cars are permitted to advance a step and when returned the foremost detained car is separated from the others and released to be moved into position to cooperate with the pick-up devices, a pivoted track section movable with said stops to which said separated car is released, and means controlled by movement of the conveyor and by the weight of the separated car for controlling the movement of the pivoted track section and stops.

In witness whereof, I have hereunto subscribed my name.

CHARLES S. HADDLESAY.

CERTIFICATE OF CORRECTION.

Patent No. 1,917,836.

July 11, 1933.

CHARLES S. HADDLESAY.

It is hereby certified that error appears in the printed specification of the above numbered patent requiring correction as follows: Page 2, line 114, claim 3, for "detailed" read "detained"; page 3, line 12, claim 4, for "and" read "the"; and that the said Letters Patent should be read with these corrections therein that the same may conform to the record of the case in the Patent Office.

Signed and sealed this 22nd day of August, A. D. 1933.

M. J. Moore.

Acting Commissioner of Patents.
